RULER

Walter Nail, Toronto, Ontario, Canada

Application February 20, 1942, Serial No. 431,675

5 Claims. (Cl. 33—107)

My invention relates primarily to rulers of the type comprising a base for resting upon paper to support an elevated member having a straight edge adapted to lie above the paper so that a pen drawn across the edge will not be liable to blot the paper.

A major object of the invention is to improve this class of ruler by a construction operative to enable the straight edge to be adjusted to and away from the base in order that it may be positioned in close proximity to the paper for the purpose of more accurately ruling lines and laying out dimensions. This object is achieved by fashioning the ruler of a piece of flexible material bent upon itself to form a base and a superimposed member with a straight edge disposed well above the paper so that blotting and smearing will not likely ensue as the pen travels along the edge; and furnishing a clamp for inwardly flexing the superimposed member to lower the 20 straight edge so that it will lie closer to the paper as occasion demands.

In the drawing,

Fig. 1 is a plan view of one form of the invention.

Fig. 2 is a cross section taken on line 2—2 thereof.

Fig. 3 is a top plan view of the device as a combined blotter holder and ruler.

Fig. 4 is a cross section taken on line 4—4 of 30 Fig. 3.

Fig. 5 is a bottom plan view of this variant form.

Fig. 6 is a detail in perspective of one end of the ruler showing more clearly the manner of 35 detachably securing the blotter.

Fig. 7 is a fragmentary view of one of the fastening devices for the blotter.

Like numerals of reference denote similar parts in each figure of the drawing.

Alluding at first to Figs. 1 and 2, the ruler is constructed of a long piece of flexible material, such as metal or a plastic substance, bent upon itself longitudinally in the form of a close return bend to produce a base 8 and a member 9 superimposed thereover with an upward inclination toward its free edge. This provides a straight edge 10 which is graduated as at 11 for use as a scale, and is also tapered in cross section and inclined downwardly, as is clearly depicted in 50 Fig. 2. The bight 12 enables the ruler to be compressed to bring the straight edge closer to the base and for this purpose it may be weakened, if found desirable, to secure the most suitable degree of flexibility. Preferably, the distal 55

edge portion of the base is supplied with a beveled face 13 to allow the straight edge to be pressed down to the paper without interference. Also, the base is made of a less width than the overlying member so that the edge 13 will be clear of the pen when drawn along the straight edge 10.

In the relaxed position of the overlying member, the straight edge will lie a distance above the base sufficient to preclude blotting and smearing in the operation of the pen therealong. The clamping device for producing the compressive action by which the straight edge is adjusted to a lower position comprises a stud 14 secured to the base and projecting through an aperture in the overlying member with a screw 15 threadedly engaged with its projecting part. It will be obvious that by turning the screw in the proper direction the desired adjustment may be brought about.

In adapting the ruler to serve as a holder for a blotter, as depicted in Figs. 3 to 7 inclusive, the base 8 is prolonged at each end, as at 16, beyond the overlying member and deformed throughout its length to accommodate a strip of blotting paper 17 in the recess 18 so that the bottom face of the strip will be substantially flush with that of the base. The strip is of a length in excess of that of the base and is applied by folding its ends over the ends 16 thereof. The ends 16 are each supplied with a fastening device 19 consisting of a flat bar of spring metal fulcrumed at 19 to one side of the respective base-end so as to swing thereover and bear upon the portion of the blotter overlying the same with sufficient tension to retain it in place.

Said bar has an upturned finger piece 20 at its free end by which it may be conveniently shifted, and adjacent thereto is a nodule 21 projecting downwardly to engage in a hole or the like formed in the base whereby it may seat itself to releasably secure the bar in its closed position. To aid in retaining the clamped portion of the blotter, the bar is desirably furnished with downwardly inclined serrations 22 along its inner edge.

The bars co-operate in the retention of the blotter strip and since they are urged inwardly in applying the strip to the base they draw it taut within the recess. To remove the strip it is only necessary to swing the bars outwardly to a releasing position.

The fastening device for the blotter is particularly suitable for a combined blotter holder

and ruler of the type herein disclosed and produces a highly efficient tool for all purposes.

What I claim is:

1. In a ruler, a base, a superimposed member carried thereby having a straight edge shiftable toward and away from the base, and means for effecting such shifting movement of the straight edge and for retaining it in the position to which it is adjusted.

2. In a ruler, a base, a superimposed member carried thereby having a straight edge adjustable to and away from the base, and a clamp device for effecting such adjustment.

3. In a ruler, a base having parallel longitudinal edges, an overlying flexible member connected to one of the longitudinal edges thereof and having a straight edge projecting forwardly of the other longitudinal edge thereof, the connection of the overlying member with the base permitting of limited flexure for enabling the straight edge to be adjusted relative to the base, and means for flexing the overlying member to effect adjustment of the straight edge.

4. In a ruler, a base having parallel longitudinal edges, an overlying flexible member connected to one of the longitudinal edges thereof and having a straight edge projecting forwardly of the other longitudinal edge thereof, the connection of the overlying member with the base permitting of limited flexure for enabling the straight edge to be adjusted relative to the base, and a screw device for flexing the overlying member to effect adjustment of the straight edge.

5. A ruler comprising a single piece of material bent longitudinally upon itself to provide a base member and a superimposed member inclined upwardly therefrom, the distal portion of the superimposed member constituting a straight edge and being downwardly sloped, a stud projecting from the base member, and a screw shouldered on the superimposed member and threadedly engaged with the stud.
